REMINDER INDEX BOX

Stephen B. Misenko, 1350 E. Boston Road,
Broadview Heights, Ohio 44147

Filed Mar. 10, 1970, Ser. No. 21,835

Term of patent 14 years

Int. Cl. D19—99

U.S. Cl. D74—2

FIG.1

FIG.5

FIG. 6

FIG. 1 is a front perspective view of a reminder index box incorporating my new design;

FIG. 2 is a top plan view;

FIG. 3 is a bottom view;

FIG. 4 is a back perspective view;

FIG. 5 is a front perspective view of another embodiment of the reminder index box shown in FIG. 1 wherein the cut-outs on the front wall are shown in a diagonally offset relationship; and

FIG. 6 is a front perspective view of still another embodiment of the reminder index box shown in FIG. 1 wherein the cut-outs on the front wall are shown in a vertically superimposed but spaced relationship.

I claim:

The ornamental design for a reminder index box, as shown and described.
